UNITED STATES PATENT OFFICE

167,797

AUTOMOBILE DOOR VISOR

John P. Groboski, Sheffield, Pa., and
Joseph G. Groboski, Chicago, Ill.

Application April 1, 1952, Serial No. 19,153

Term of patent 14 years

(Cl. D14—6)

To all whom it may concern:

Be it known that we, John P. Groboski, a citizen of the United States, residing at Sheffield, Pennsylvania, and Joseph G. Groboski, a citizen of the United States, residing in Chicago, Illinois, have invented a new, original, and ornamental Design for an Automobile Door Visor, of which the following is a specification, reference being had to the accompanying drawing forming a part hereof.

Fig. 1 is a perspective view of the automobile door visor, showing my new design.

Fig. 2 is a top view thereof.

Fig. 3 is a sectional view on line 3—3 of Fig. 2.

We claim:

The ornamental design for an automobile door visor, as shown.

JOHN P. GROBOSKI.
JOSEPH G. GROBOSKI.
